(57) **CLAIM**

The ornamental design for an adjustable adaptor for a prosthetic leg, as shown and described.

DESCRIPTION

FIG. 1 is a first perspective view of an adjustable adaptor for a prosthetic leg;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a first perspective view showing a condition in sliding the upside parts thereof;

FIG. 10 is a second perspective view showing a condition in sliding the upside parts thereof;

FIG. 11 is a front view showing a condition in sliding the upside parts thereof;

FIG. 12 is a rear view showing a condition in sliding the upside parts thereof;

FIG. 13 is a left side view showing a condition in sliding the upside parts thereof;

FIG. 14 is a right side view showing a condition in sliding the upside parts thereof;

FIG. 15 is a top view showing a condition in sliding the upside parts thereof; and,

FIG. 16 is a bottom view showing a condition in sliding the upside parts thereof.
